UNITED STATES PATENT OFFICE

JOHN WILLIAM SCOTT, OF FLUSHING, NEW YORK

EDGING

Application filed January 8, 1930. Serial No. 419,391.

This invention is an improvement in edgings, and more particularly in ornamental and protective edgings for heavy floor coverings, such as linoleum and the like.

8. In practice, thick floor coverings, such as linoleum and the like, are provided with an edging of metal, the edging being secured to the floor at the border of the covering, and forming an ornamental finishing edge for the

10. cover.

Such devices are usually constructed with an upper face rounding at the outer side, and slightly undercut at the inner side, to fit the similarly shaped edge of the covering, and 15 they may extend entirely around the border of the covering, or at any desired point thereof, such for instance, as doorways, serving thus as a protection for the edge of the covering.

20. In the usual practice, the edging is secured to the floor by securing means, such for instance, as screws or nails, which are passed through openings in the edging.

One of the primary objects of the present 25 invention is the provision of a form of edging, having means on the underside thereof, and concealed when the edging is in place, for receiving securing means, whereby the edging may be connected to the floor, without 30 the securing means being visible.

Another object is to provide in such a form 35 of edging, a securing means of a character such that it may be attached to the edging, at the time when the edging is secured to the floor, and which is adjustable longitudinally of the edging to any desired position.

With these and other objects in view the 40 invention consists in the construction and novel combination of parts fully described hereinafter, illustrated in the accompanying drawings, and pointed out in the claims appended hereto, it being understood that various changes in the form, proportion, size 45 and minor details of construction within the scope of the claims, may be resorted to without departing from the spirit of the invention.

50. In the drawings forming a part hereof:— Fig. 1 is a perspective view of a part of a

floor, showing the floor covering, and the edging in place, parts being in section.

Fig. 2 is a similar view of an alternate form of edging with the edging and securing means detached, and with the edging in 55 section.

Fig. 3 is a plan view showing the manner of using the edging.

Fig. 4 is a view similar to Fig. 2, showing an alternate form of securing means. 60

In the embodiments of the invention shown in Fig. 1, the edging indicated at 1, of the usual shape, and of any desired material, is provided in its under plane face, with an undercut or dovetail groove 2. The said groove extends the full length of the edging and it is designed to receive a portion of a securing means, whereby the edging may be connected to the floor. 65

This securing means may be a nail or the like, the head of the nail being inserted in the groove, as shown in Fig. 4, in which case the edging is connected to the floor, by hammering on the upper face of the edging, after the securing means is inserted. Preferably 70 the securing means fits the groove somewhat closely. As for instance, with a tack or nail, as shown in Fig. 4, the head of the tack or nail should fit against the bottom of the groove, so that when the edging is secured 75 in place, there is no lost motion. 80

In Figs. 1 and 3, the securing means is in the form of a plate 3, of some suitable material, as for instance, sheet metal, and the plate is provided at one edge with a rib 4, 85 which is of the same cross-sectional shape as the groove, and is of a size to fit snugly in the groove. In the present instance, the rib is formed by bending the edge of the sheet material to form a hollow rib, of the shape 90 desired, and the plate is provided with one or more openings 5, for enabling the passage of means 6, such as a screw, for engaging the flooring 7 to hold the plate and the edging in place. The openings 5 are reamed as shown, 95 to receive the head of the screw, so that the screw is flush with the upper face of the plate. The floor covering 8, of linoleum or the like, has its marginal edge beveled slightly as shown at 9, to fit against the similarly shaped 100

edge 10 of the edging, and the plate 3 is received beneath the linoleum, as clearly shown in Fig. 1, and is covered and concealed by the linoleum and the edging, so that no part thereof is visible.

With this construction, the lower face of the edging will be spaced slightly above the floor, as shown in Fig. 1, a distance corresponding to the thickness of the plate 3. In practice, these plates are very thin, so that the space between the edging and the floor is not noticeable. In the drawings, the plate is shown as exaggerated in thickness. At the inner edge of the plate, the linoleum will 15 adjust itself so that the plate is not noticeable.

In Fig. 2, the edging 11 is similar to the edging 1, having the groove 12 in its under-face, and the securing means 13 has the rib 20 14 for engaging the groove, and the openings 15 for receiving the screws. The under-face of the edging at the inner side of the groove is cut away, a distance corresponding to the thickness of the plate 13, so that the 25 under-face of the edging outside of the groove rests flat against the floor. That is, this part of the underface is flush with the face of the plate 13.

While the underface of the edging at the 30 inner side of the groove is spoken of as cut away, there is no cutting. This term is for convenience only, the edging being usually formed by extrusion through a die, so that the same process is followed in making the 35 edging 11 as in making the edging 1, no additional operation or labor being required.

In some cases, the plates 3 or 13, which are precisely the same may be dispensed with and the edging may be secured by a nail or tack 40 indicated at 16. In Fig. 4, the edging 17 as shown, has a groove 18, and the head 19 of the nail or tack, fits snugly within the groove, the head preferably abutting the bottom of the groove, so that when the nail is driven home 45 by hammering on the edging, there will be no lost motion or play of the edging vertically.

It will be apparent that the invention in its broadest form is the undercut groove in 50 the underside of the edging, and that the securing means 3 or 13, as the case may be, is not necessarily of any great width. These plates might be merely strips. The securing means is essentially a member having a head 55 fitting within the groove, and may be either a strip with a transverse head at one end, or a nail or the like.

What is claimed as new is:—

1. An edging for floor coverings having in 60 the lower face thereof a longitudinally extending groove with undercut side walls, and securing plates for connecting the edging with a floor, each plate having at one end a head shaped to fit and slide within the groove, 65 that portion of the underface of the edging

at the inward side of the groove being cut away a depth corresponding to the thickness of the plate.

2. For use in combination with a floor and a sheet of floor surfacing material such as 70 linoleum of substantial thickness having an edge located in an open area of the floor surface, a metal finishing strip of vertical thickness corresponding to that of the floor surfacing material, having a substantially flat 75 bottom face confronting the floor, an inward substantially upright face fitting against said edge face of the surfacing material, a substantially rounded upper and outer face, and a longitudinal undercut channel, substantially centrally located in the under-face of the strip, and a plurality of thin 80 retaining plates projecting laterally from the strip substantially in the plane of its under-face, the plates being thin and flat and adapted to lie between said surfacing material and the floor and having means for floor attachment, and each plate having at its edge located beneath the strip a head formation 85 projecting upward and of a cross-section to fit slidably in the undercut channel, the plates being thus independently attachable and adjustable longitudinally of the strip. 90

3. For use in combination with a floor and a sheet of floor surfacing material such as 95 linoleum of substantial thickness having an edge located in an open area of the floor surface, a metal finishing strip of vertical thickness corresponding to that of the floor surfacing material, having a substantially flat 100 bottom face confronting the floor, an inward substantially upright face fitting against said edge face of the surfacing material, a substantially rounded upper and outer face, and a longitudinal undercut channel, substantially centrally located in the under face of the strip, and a plurality of thin retaining plates projecting laterally from the strip substantially in the plane of its under-face, 105 the plates being thin and flat and adapted to lie between said surfacing material and the floor and having means for floor attachment, and each plate having at its edge located beneath the strip a head formation projecting upward and of a cross-section to fit slidably 110 in the undercut channel, the plates being thus independently attachable and adjustable longitudinally of the strip, the under-face of the strip at the inward side of the undercut channel being located in a plane above that of the outward portion of said face a distance equal to the plate thickness, whereby said outer portion of the underface of the strip is in direct flatwise contact with 115 the floor surface. 120

Signed at New York City, in the county of New York and State of New York, this 7th day of January, A. D. 1930.
